(57) **CLAIM**

The ornamental design for a muzzle brake with muzzle
brake core, as shown and described.

DESCRIPTION

FIG. 1 is a bottom front perspective view of the muzzle
brake with muzzle brake core;

FIG. 2 is a top front perspective view of the muzzle brake
with muzzle brake core;

FIG. 3 is a bottom perspective view of the muzzle brake with
the muzzle brake core removed;

FIG. 4 is a first side view of the muzzle brake with muzzle
brake core;

FIG. 5 is a second side view of the muzzle brake with muzzle
brake core;

FIG. 6 is a third side view of the muzzle brake with muzzle
brake core;

FIG. 7 is a fourth side view of the muzzle brake with muzzle
brake core;

FIG. 8 is a bottom up view of the muzzle brake with muzzle
brake core;

FIG. 9 is a top down view of the muzzle brake with muzzle
brake core;

FIG. 10 is a bottom front perspective view of the muzzle
brake with the muzzle brake core removed;

FIG. 11 is a first side view of the muzzle brake with the
muzzle brake core removed;

FIG. 12 is a second side view of the muzzle brake with the
muzzle brake core removed;

FIG. 13 is a third side view of the muzzle brake with the
muzzle brake core removed;

FIG. 14 is a fourth side view of the muzzle brake with the
muzzle brake core removed;

FIG. 15 is a fifth side view of the muzzle brake with the
muzzle brake core removed;

FIG. 16 is a bottom up view of the muzzle brake with the
muzzle brake core removed;

FIG. 17 is a top down up view of the muzzle brake with the
muzzle brake core removed;

FIG. 18 is a bottom front view of the muzzle brake core;

FIG. 19 is a top front view of the muzzle brake core;

FIG. 20 is a first side view of the muzzle brake core;

FIG. 21 is a second side view of the muzzle brake core;

FIG. 22 is a third side view of the muzzle brake core;

FIG. 23 is a fourth side view of the muzzle brake core;

FIG. 24 is a bottom up view of the muzzle brake core; and,

FIG. 25 is a top down view of the muzzle brake core.
